(57) **CLAIM**

The ornamental design for a reach stacker, as shown and described.

DESCRIPTION

FIG. 1 is a front view of the reach stacker showing our new design:

FIG. 2 is a rear view thereof;

FIG. 3 is a left side view thereof;

FIG. 4 is a right side view thereof;

FIG. 5 is a top (plan) view thereof;

FIG. 6 is a bottom view thereof;

FIG. 7 is a front view showing a transparent portion of the reach stacker showing our new design:

FIG. 8 is a rear view showing a transparent portion thereof;

FIG. 9 is a left side view showing a transparent portion thereof; and,

FIG. 10 is a right side view showing a transparent portion thereof.

In the elevational view showing a transparent portion, the portion which gives the slash is transparent. In the rear elevation showing a transparent portion, the portion which gives the slash is transparent. In the left-hand side view which shows a transparent portion, the portion which gives the slash is transparent. In the right-hand side view which shows a transparent portion, the portion which gives the slash is transparent.
